UNITED STATES PATENT OFFICE.

EDWARD STERN, OF PHILADELPHIA, PENNSYLVANIA.

PROJECTILE.

SPECIFICATION forming part of Letters Patent No. 423,829, dated March 18, 1890.

Application filed April 19, 1889. Serial No. 307,827. (No model.)

To all whom it may concern:

Be it known that I, EDWARD STERN, a citizen of the United States, residing in the city and county of Philadelphia, State of Pennsylvania, have invented a new and useful Improvement in Projectiles, which improvement is fully set forth in the following specification and accompanying drawings.

My invention consists of a projectile having a cylinder or sleeve adapted to receive air or other gas under pressure, and which is fitted with a piston or plunger which is provided with mechanism for resisting the pressure of air or other gas which is forced into the interior of the cylinder or sleeve. The mechanism employed being of such construction as to permit the entrance of the plunger or piston farther within the sleeve when the sleeve is impelled forward through the force of an explosion of gunpowder or other substance in its rear, said sleeve, containing the air or gas under pressure, is to be placed between the projectile containing dynamite or other high explosive and the seat of the explosive or force used in impelling or throwing the projectile from the gun, the rear portion of the projectile being adapted to enter the cylinder or sleeve when the latter is impelled forward, thus forming an efficient air-cushion between the projectile and the seat of the explosive, thereby reducing the shock imparted to a projectile when forced from a gun in the usual manner.

The invention may also be employed in connection with the firing of solid shot, and when so employed will reduce the sudden shock which tends to burst the cannon.

Other advantages resulting from the use of my invention will be fully set forth.

Figure 1 represents a longitudinal section of a projectile embodying my invention. Fig. 2 represents a longitudinal section of a modification.

Similar letters of reference indicate corresponding parts in the two figures.

Referring to the drawings, A designates a projectile of suitable form, having a chamber B for dynamite or other high explosive.

C designates a chamber for containing compressed air or other gas, the same being formed in a sleeve D, the forward end of which freely encircles the breech end of the

projectile A, which engages with the sleeve D by means of the spring-pressed tongues E, said tongues being so constituted that while remaining in their primary position they retain the projectile A within the sleeve D and permit the sleeve D to advance freely over the projectile A when the sleeve is impelled forward by an explosion in its rear.

To the rear wall of the sleeve D is attached a pipe F, whereby air or other gas under pressure may be forced into the chamber C, said pipe being covered, when desired, by a cap G, which is screwed or otherwise attached to the contiguous end of the sleeve D.

Within the chamber C, toward the forward end of the same, and consequently at the rear of the projectile, is a plunger H, between which and the projectile are buffers J, of rubber or other elastic material, which may be glued to the surface of the piston, and provide a cushion between the piston and the projectile. To the periphery of the plunger are fitted dogs K, which enter recesses in the inner face of the sleeve D, said dogs being of such construction that while they prevent the gas or air under pressure from expelling the piston from the sleeve D they will permit the free advance of the sleeve forward over the piston when it is impelled by a force or explosion from the rear. This latter action of the mechanism of the plunger is more marked when a mass or projectile bearing upon it prevents or tends to check the forward motion which would be imparted to it by the sleeve D when the sleeve is impelled forward.

The head of the projectile has at its back a shoulder L, which may be provided with a step shape, as shown in Fig. 1, for engagement with the forward end of the sleeve D, which end of the sleeve D may be shaped to receive the step shown in the shoulder L; and, further, the forward end of the sleeve D may be provided with a layer of elastic substance M.

To the projectile at the rear of the shoulder L are catches or tongues N, which are adapted to engage with the recesses or the inner surface of the sleeve when the latter is forced forward over the projectile. Previous to firing and after the explosion, when the sleeve D is forced forward over the projectile A,

there may be a partial escape of gas from the chamber C into the space between the shoulder L and the forward end of the sleeve D. The air or other gas thus confined between 5 the head of the projectile, the sleeve, and the sides of the cannon will aid the air-cushion formed in the chamber C in preventing shock to the projectile containing the dynamite or other high explosive.

10 In Fig. 2 the plunger H is formed at or constituted by the rear of the projectile, the periphery of the plunger carrying dogs K, which engage with the recesses in the wall of the sleeve D. Projecting rearward from the 15 plunger, at the center thereof, is a stud P, which is adapted to enter the bore of the pipe F when the sleeve is impelled forward over the projectile. On the inner face of the sleeve, behind the plunger H, are serrations O, with 20 which the dogs K are adapted to engage when the sleeve is impelled or forced forward over the projectile. The action of the dogs N will tend to prevent the sleeve from returning 25 from the forward position which it has been compelled to assume on the projectile.

In Fig. 2 it will be seen that the diameter of the projectile at the breech end thereof is such that the forward end of the sleeve fits snugly thereover as well as over the plunger 30 H. The diameter of the projectile between the sleeve and the shoulder L is reduced, by which provision, when the sleeve is forced forward over the projectile, it moves with greater freedom, owing to the decreased frictional contact of the adjacent parts.

35 The diameter of the wall of the chamber C at the portion rear of the plunger H is greater than the portion with which the plunger is in contact, so that when the sleeve advances it 40 moves with greater freedom, owing to the decreased frictional contact of the adjacent parts. Previous to firing the powder or other explosive used in forcing the sleeve and projectile from the gun, and after the explosion, 45 when the sleeve is being forced forward over the projectile, there may be a partial escape of the compressed air from the chamber C into the space between the shoulder L of the projectile and the forward end of the sleeve 50 D and sides of the cannon. The air or other gas being thus confined between the head of the projectile, the front of the sleeve and the sides of the cannon will form an air-cushion, aiding the cushion formed in the chamber C 55 in preventing shock being communicated to the projectile containing the dynamite or other high explosive. The distance from the shoulder L to the forward end of the sleeve D will be equal to the distance from the plunger H to the rear surface of the chamber C, thus aiding in the formation of efficient air-cushions.

60 In the sleeves D, near the forward end thereof, are the perforations a and b for receiving pins or other implements used in order to facilitate the seating of the tongues E and dogs K into their respective recesses in the sleeve,

said perforations being afterward closed by plugs or screws in any suitable manner.

The operation is as follows: The chamber 70 C is charged with air or gas under pressure, said chamber being determined by the plunger H and rear and side walls of the sleeve D, and having its joints as tight as found practicable. The pressure within the chamber 75 may be raised to such a point as is found in practice to form the best air-cushion for the purpose of decreasing the shock communicated in the usual method of discharge. The projectile, with its attached parts in the 80 position shown in the drawings, is inserted in the cannon or fire-arm, and the latter discharged in any suitable manner. As the sleeve is impelled it advances and rides over the body of the projectile, and the air in the 85 chamber C provides a cushion, which decreases the shock imparted to the projectile, as has been stated, an additional cushion being provided by the channel formed around the projectile between the shoulder L and forward end of the sleeve, said channel being circumscribed by the bore of the cannon. In the new position attained by the sleeve the tongues N interlock with the sleeve, an additional interlocking action being provided 90 by the dogs K, if so desired.

I do not limit myself to the precise form of mechanism shown as holding the piston in its original position or for holding the sleeve upon the projectile when it is forced forward 100 upon the latter, but will in practice use any known mechanical device which will most suitably effect the objects sought. In practice any suitable packing for rendering the junction of the piston and sleeve air-tight or 105 any known form of construction aiding the object sought may be employed. Any suitable fuse for exploding the dynamite or other high explosive at the desired point may be employed.

Having thus described my invention, what I claim as new, and desire to secure by Letters Patent, is—

1. A projectile having a chamber for high explosive material therein and provided with 115 a sleeve embracing the breech end thereof, the said sleeve having an air-chamber and a plunger at the breech end of the projectile and adapted to move in said air-chamber, said parts being combined substantially as described.

2. A projectile having a chamber for high explosive material and a chamber for compressed air or gas rearward of the same, formed by a plunger at the breech end of the 120 projectile, and a sleeve which is movably fitted to the projectile and capable of riding thereover, as stated.

3. In a projectile for high explosive material, having a chamber rearward thereof for air or gas under pressure, a sleeve movably connected with the projectile and capable of riding thereover, said projectile and sleeve 130 having means for interlocking the same when

the sleeve is advanced, substantially as described.

4. A projectile having the shoulder L on its side and provided with a sleeve embracing the breech end thereof and adapted to ride thereon, said sleeve having at its forward end a depression coinciding with said shoulder on the projectile, and a plunger at the breech end of said projectile, having locking-dogs 10 therein, the latter being adapted to engage in recesses in the sleeve, said parts being combined substantially as described.

5. A projectile having a central portion of reduced diameter and provided with a sleeve 15 embracing the breech end thereof and adapted to ride thereon, the said sleeve having an air-chamber of increased diameter at the end

farthest from the breech end of the projectile, said parts combined substantially as described.

6. A projectile having its front end shouldered, a central portion of reduced diameter, and a breech end of greater diameter than the central portion thereof, a sleeve embracing said breech portion and adapted to abut 25 against said shouldered front of the projectile, said sleeve having an air-chamber thereon of increased diameter at the end farthest from the breech portion of the projectile, said parts combined substantially as described.

EDWARD STERN.
